UNITED STATES PATENT OFFICE

WALTER S. COCHRANE, OF DETROIT, MICHIGAN, ASSIGNOR TO CHRYSLER CORPORATION, OF DETROIT, MICHIGAN, A CORPORATION OF DELAWARE.

INTERNAL-COMBUSTION ENGINE

Original application filed April 20, 1927, Serial No. 185,208. Divided and this application filed December 9, 1927. Serial No. 238,791.

This invention relates to internal combustion engines, more particularly to an oil filler therefor, and is a division of my copending application, Serial No. 185,208, filed April 5 20, 1927.

In ventilating the crankcase of an internal combustion engine, it is desirable to admit air into the crankcase through the oil filler, thru which lubricant is supplied to the crankcase.

10 It is an important object of this invention to provide a novel cover for the filler pipe which may be adjusted with respect to the filler pipe, to vary the amount of air admitted therethrough, without admitting dirt.

15 Another object of the invention is to provide a hinged cap for the cover which may be opened for filling the crankcase with lubricant without disturbing the other portions of the cover.

20 Other objects and advantages will more fully appear from the following description taken in connection with the accompanying drawings in which:

25 Fig. 1 is a longitudinal sectional view, partly through the crankcase and partly through the valve chamber of an internal combustion engine.

Fig. 2 is a vertical sectional view through the engine.

30 Fig. 3 is a sectional view on line 3—3 of Fig. 2 showing the preferred form of my invention.

Fig. 4 is a plan view of the filler, parts being broken away.

35 Referring to the drawings, I have shown an internal combustion engine in which an air current is caused to flow through the crankcase in a circular direction. A cylinder head 10, cylinder block 12 and oil pan 14 have been shown, as of usual design. The crank-shaft 16, connecting rods 18, pistons 20, cam-shaft 22 and valve mechanism 24 have been shown adapted to operate in the usual manner. The lower portion of the cylinder block 12 and the oil pan 14 form a chamber 26 commonly called the crankcase in which the crankshaft rotates. A filler pipe 30 is mounted on the side of the crankcase at its forward end and is designed to admit air to the crankcase 26. The rotation of the crankshaft

causes a circular motion of the air and the air is then directed into the valve chamber 34, through openings 36, and out through a tail pipe 38 at the rear of the engine.

In order that clean air may be properly admitted to the crankcase chamber, I have provided a novel filler which comprises a tubular member 40, open at both ends, the lower end of which is in communication with the crankcase chamber 26. At the opposite or outer open end of the filler, I have provided a cover which comprises an outer member 42, cap 44 and sleeve 46. Openings 48 are provided in the side of the member 40 and the sleeve 46 is provided with openings 50 adapted to register with the openings 48. The sleeve 46 fits the outer periphery of the tubular member 40 and is provided with an inwardly turned flange 52 which rests on the upper edge of the member 40. The sleeve 46 is angularly movable for closing or opening the openings 48.

The outer member is spaced from the tubular member 40 and sleeve 46, having an inwardly turned flange 54 adapted to seat on the flange 52 of the sleeve. A screw 56 secures the outer member in position and also limits the angular movement of the sleeve 46; the screw being received in a slot 58 in the flange 52. A downwardly extending flange 60, on the member 42 shields the openings 48 so that lubricant may be directed past the openings into the crankcase.

The lower edge of the outer member 42 is provided with fins 62 which tend to separate the dirt from the air drawn into the filler pipe through the space between the tubular member 40 and outer member 42 and through the openings 48. The outer member 42 has been shown in two pieces to facilitate manufacture but it is to be understood that it may be formed from one integral member. A struck up member 64, from the sleeve 46 projects through a slot 66 in the flange 54, providing a means for angularly moving the sleeve 46 to open or close the openings 48.

The cap 44 is hinged to the outer member 42, as at 68, adapted to close the open end of the filler. A resilient lip 70 engages a depression 72 in the outer member 42 to hold the cap in closed position.

While one particular adaptation of my invention has been illustrated and described in detail, it is to be understood that various changes including size and arrangement of parts may be made without departing from the spirit of my invention and it is not my intention to limit its scope other than by the terms of appended claims.

What I claim is:

5. In an engine of the class described, a crank case chamber, an oil filler for said chamber having an opening at its outer end and openings in the side thereof, a cover for said oil filler extending over said side openings and spaced from the side wall of the filler, means for opening and closing said last named openings, and means for directing a current of air through the space formed between said cover and the wall of said filler through said side openings into said filler and said crankcase.
10. 2. In an engine of the class described, a crank case chamber, an oil filler for said chamber having an opening at its outer end and openings in the side wall thereof, a cover for said oil filler extending over said side openings and spaced from the side wall of the filler, a plurality of fins at the lower edge of said cover between said cover and said filler wall, and means for directing a current of air through the space formed between said cover and the wall of said filler through said side openings into said filler and said crankcase.
15. 3. In an engine of the class described, a crank case chamber, an oil filler for said chamber having an opening at its outer end and openings in the side wall thereof, a cover for said filler having a central opening and an inwardly extending flange around the periphery of said opening adapted to be received in the open end of said filler, means for securing said cover to said filler, a portion on said cover extending outwardly from
20. 45. 4. In an engine of the class described, a crank case chamber, an oil filler for said chamber having an opening at its outer end and openings in the side wall thereof, a cover for said filler having a central opening and an inwardly extending flange around the periphery of said opening adapted to be received in the open end of said filler, means for securing said cover to said filler, means for opening and closing the openings in the side wall of said filler operable through said cover, a portion on said cover extending outwardly from said filler and downwardly over and spaced from the openings in the side of said filler, and a hinged cap secured to said cover for opening and closing the opening in said cover.

5. In an engine of the class described, a crank case chamber, an oil filler for said chamber having an opening at its outer end and openings in the side wall thereof, a cover for said filler having a central opening and an inwardly extending flange around the periphery of said opening adapted to be received in the open end of said filler, means for securing said cover to said filler, a portion on said cover extending outwardly from said filler and downwardly over and spaced from the openings in the side of said filler, a plurality of fins at the lower edge of said cover between said cover and said filler wall, and a cap for closing the opening in said cover.
